UNITED STATES PATENT OFFICE.

DINO CHIARAVIGLIO, OF ROME, ITALY.

FIREARM.

1,297,798.

Specification of Letters Patent. Patented Mar. 18, 1919.

Application filed October 17, 1916. Serial No. 126,072.

To all whom it may concern:

Be it known that I, DINO CHIARAVIGLIO, a subject of the King of Italy, residing at 102 Via Nazionale, Rome, Italy, have invented certain new and useful Improvements in or Relating to Firearms, of which the following is a specification.

This invention relates to multicharge fire arms, in which two or more charges are arranged in chambers originally separated from each other and act separately at suitable intervals of time, for the purpose of transmitting in the best possible manner the energy of the explosive to the projectile while it is passing through the barrel.

The invention comprises a new arrangement of the partial propelling charges in multicharge fire arms, and is illustrated in the accompanying drawings, in which:

20 E (Figure 1) is the wall of a muzzle-loading gun, A the projectile, which, instead of having a practically flat base, is provided with an extension B which engages in a suitable recess provided in the breech F. In this way two chambers C and D are obtained, in each of which is placed a propelling charge. More chambers for additional propelling charges could be obtained by an equal number of restrictions in the 30 diameter of the extension B, as shown in Fig. 2. The communication between the chambers C and D (Fig. 1) is established by means of a small conduit —e—f— of suitable size, in which can be located a fuse, the speed of combustion of which has been suitably calculated.

If one of the charges, for instance that at D, is fired through the touch-hole —g—, the ignition will spread to the other in a 40 manner determined by the size and shape of the passage ef, or by the speed of combustion of the fuse. By giving the various parts suitable dimensions, it is thus possible to insure that both charges should begin or cease to act at different moments.

The ignition of the different portions of the charge could also be regulated or produced by the movement of the projectile; it is also possible to arrange the charge so 50 that each of its separate parts plays part in the movement of the projectile. Moreover, muzzle-loading or breech-loading arms could be designed in which the obturator constitutes a part of the walls of one or 55 more charge chambers. The arrangement could also be such that the projectile con-

tains the whole or a part of the propelling charge.

Fig. 3 shows an arrangement as could be adopted in breech-loading guns. The two 60 propelling charges are contained in a metal casing —m— in which the projectile is firmly inserted. To load the gun firstly the breech —o— is taken apart by unscrewing it from the rest of the gun, secondly the projectile is inserted with the casing —m—, containing the propelling charges, attached to it; the breech is then screwed up again in position, and the gun is ready to be fired by striking the striker —p— which will 70 explode the cap —q— and thus set fire to the first propelling charge. The second propelling charge will be exploded by the gases of the first charges passing through the passage ef, or by a fuse located in said passage, 75 or directly by the gases of the first charge as soon as the extension B of the projectile has moved far enough to allow the gases of the first charge to come into direct contact with the second charge at D. 80

As above described and shown by the drawings the invention mainly consists in obtaining the different chambers for the propelling charges by modifying the shape of usual projectiles and particularly by 85 means of a rearward extension of the projectile; therefore such chambers are not prepared in the gun or in a cartridge except in the case of Fig. 3, but are originated by the projectile itself at the moment of its insertion 90 into position in the barrel of the gun. An important feature of this arrangement is that the walls of the gun are also the walls of the charge chambers; thereby doing away with the necessity of separating 95 the different chambers with a sufficient thickness of metal to stand the strain produced by each of the propelling charges acting separately, as is the case with many of the similar arrangements hitherto known. 100 Another important advantage of my arrangement compared with others is that the intervals of time at which each of the propelling charges begins to act can be perfectly regulated either by proportioning in 105 the right way the size of the passages from one chamber to the other, or by suitably regulating the speed of combustion of a time fuse or finally by proportioning the charges and the dimensions of the gun in such a 110 way as to make the gases produced by the combustion of each charge come into direct

contact with the succeeding charge at the right moment, determined by a particular position of the projectile in its forward movement along the barrel of the gun.

The arrangement described has also the advantage of being very simple in construction and thus capable of a very easy application, and of permitting a very strong and comparatively light construction of the gun, owing to the fact that the charge chambers are not prepared in the gun barrel, but are originated by the peculiar shape of the projectile when this is in position in the gun, and that the walls of the gun also work as walls for all the charge chambers.

Having now particularly described and ascertained the nature of my said invention and in what manner the same is to be performed, I declare that what I claim is:

1. In combination, a gun having the inner end of the bore formed with a recess, the walls of said recess being disposed at right angles to the inner walls of the bore and a projectile snugly fitting within the bore of said gun, an extension formed at the base of said projectile and snugly fitting within said recess, and a casing formed on said projectile, said casing being of a contour corresponding to the inner end of the bore and to said recess for the purpose described.

2. In combination, a gun having the inner end of the bore formed with a recess, the walls of said recess being disposed at right angles to the inner end of the bore, a projectile snugly fitting within the bore of said gun, and an extension formed at the

base of said projectile and snugly fitting within said recess, said projectile and said extension being normally spaced from the inner end of said bore and said recess to provide firing chambers.

3. In combination, a gun having the inner end of the bore formed with a series of concentrically disposed recesses, said recesses being of graduating diameters, said gun being formed with a fuse channel connecting said recesses to the said bore of the gun, and a projectile snugly fitting within the bore of the gun and having its face formed with a plurality of concentrically disposed extensions, said extensions being of graduating diameters and snugly fitting within said recesses.

4. In combination, a gun having the inner end wall of the bore formed with a concentrically disposed recess, a projectile snugly fitting within said barrel and having the base thereof normally spaced from the end walls of the bore of said gun to provide a firing chamber, and an extension formed at the base of said projectile and snugly fitting within said recess, the outer end of said extension being spaced apart from the inner end of said recess to provide a second firing chamber, said gun being formed with a passage to connect one chamber with the other chamber.

In witness thereof I have hereunto set my signature in the presence of two witnesses.

DINO CHIARAVIGLIO.
